UNITED STATES PATENT OFFICE.

HERBERT L. FRITZ, OF NEWARK, NEW JERSEY.

DESIGN FOR A CONFECTION.

54,074.

Specification for Design.

Patented Nov. 4, 1919.

Application filed October 31, 1917. Serial No. 199,589. Term of patent 14 years.

To all whom it may concern:

Be it known that I, HERBERT L. FRITZ, a citizen of the United States, residing at Newark, in the county of Essex and State of New Jersey, have invented a new, original, and ornamental Design for Confections, of which the following is a specification, reference being had to the accompanying drawings, forming part hereof.

Figure 1 is a plan view of my improved design; and

Fig. 2 a side elevation of the same.
I claim:

The ornamental design for a confection, having the configuration shown, and central depressions on both faces, providing a continuous, imperforate web located centrally of the confection.

HERBERT L. FRITZ.
